UNITED STATES PATENT OFFICE.

JAMES S. CROSSLEY, OF SOLVAY, NEW YORK, ASSIGNOR TO PASS AND SEYMOUR, INCORPORATED, OF SOLVAY, NEW YORK, A CORPORATION OF NEW YORK.

SHADE-HOLDER.

1,203,101.

Specification of Letters Patent. Patented Oct. 31, 1916.

Application filed September 24, 1915. Serial No. 52,449.

To all whom it may concern:

Be it known that I, JAMES S. CROSSLEY, a citizen of the United States, and resident of Solvay, Onondaga county, State of New York, have invented certain new and useful Improvements in Shade-Holders, of which the following is a specification.

This invention relates to shade and globe holders and the principal object is to provide such a device with few parts which will securely clamp the shade holder to its support and which will provide strong means for retaining the shade or globe in place in the shade holder.

15 The above and other objects and the novel features of the invention will be apparent from the following description taken in connection with the drawing in which:

Figure 1 is a side elevation of a shade holder embodying my invention secured in place on an electric lamp socket and supporting a shade. Fig. 2 is a view showing the shade holder in cross-section and showing in elevation the socket to which the shade holder is attached; and Fig. 3 is a detail cross-sectional view of one of the shade retaining screws and showing its connection to the shade holder shell.

Referring to the drawing 10 designates a 30 cylindrical socket shell substantially of uniform diameter from top to bottom except for an integral circumferential exterior bead 11 near the lower edge which is of greater outer diameter than the socket shell 10 above and below it. The usual cap 12 telescopically fits over the upper end of the shell 10 and is secured thereto by screws 13 or other suitable means. The shell 10 and cap 12 together form the casing for the usual electric lamp socket (not shown) which carries the incandescent lamp 14.

The shade holder proper comprises a shell 15 provided at the upper end with a threaded neck 16, the upper edge of the neck being 45 rolled upon itself inwardly as at 17 to provide a double thickness of metal at the upper end of the shell. The interior diameter of the upper end of the neck at the point 17 is substantially the same as the exterior diameter of the socket shell 10 and the double thickness at the upper end holds that part of the neck at a distance equal to the height of the bead 11, the upper end 18 of the shade holder 15 engaging against the lower 55 side of the bead 11.

The device for clamping the edge 18 of the shade holder against the lower side of the bead 11 comprises a returning ring 19 which has a portion 20 at the outer lower end thereof threaded to fit the threads on 60 the neck 16 and the upper edge thereof is turned inwardly as at 21 and has a diameter substantially the same as the outer diameter of the socket casing 10. The lower side of the inturned edge 21 rests on the upper side 65 of the bead 11 and when the threaded parts are interengaged with one another the ring 19 clamps the upper edge of the shell 15 securely in place. A portion of the outer face of the ring 19 opposite the bead 11 is 70 knurled as at 22 to provide a better grip for turning the ring.

When securing the shade holder shell 15 to the casing 10 the neck 16 is slipped over the lower end of the shell until the upper 75 edge 18 of the neck abuts against the lower side of the bead 11 and the retaining ring 19 is slipped over the upper end of the socket shell 10 and screwed onto the neck 16 until the parts are clamped to the supporting 80 bead 11. It will be seen that the ring 19 must be located on the shell 10 either before the wires are connected to the socket or before the shell 10 is slipped over the lamp socket and before the cap 12 is secured 85 thereto, as it is not possible to slip the ring upwardly over the bead 11 on account of the fact that the inturned flange 21 is smaller in diameter than the bead 11. The neck of the shade holder and the threaded connection between the shell and ring are entirely 90 below the bead 11.

The shell 15 has a depending flange 23 to which the globe or shade 24 is attached. The means for holding the globe or shade in 95 place comprises a number of thumb screws 25, three in the present instance, located at equal intervals on the flange 23. The thumb screws 25 consist of heads 26 and threaded shanks 27, the inner ends of which extend 100 to the inner side of the flange 23 and engage under the usual outwardly turned flange on the neck of the globe 24. The threaded portions of the thumb screws rotate in correspondingly interiorly threaded 105 bushings 28 fitted in holes 29 in the flange 23. The holes 29 are located at the centers of outwardly pressed portions 30 of the flange 23. The depressed portions 30 are square or angular as shown in Fig. 2 to re- 110

ceive the square or angular heads or flanges 31 on the inner ends of the bushings 28 so as to prevent the bushings from turning in the holes 29 when the screws 25 are turned. As 5 shown the heads 31 are countersunk so that they will be flush with the interior wall of the flange 23. The washer 32 surrounds the bushing 28 and fits against the outer surface of the flange 23 and an outwardly turned 10 flange 33 at the outer end of the bushing 28 holds the washer 32 and the bushing firmly in position in the hole 29.

The advantages of the construction will be apparent from the foregoing description 15 and while the device has been shown in detail it is not intended to limit the invention as slight changes in the device may be made without departing from the spirit of the invention.

20 Having thus described my invention what I claim and desire to secure by Letters Patent is:

1. A shade holder comprising a shell provided with shade or globe engaging means 25 and having a threaded neck, the end of said neck being adapted to engage one side of a shade holder supporting bead integral with the lower end of a socket shell, and a retaining device having a threaded portion at one 30 end capable of engaging said threaded neck and also provided with integral inwardly extending means at the other end thereof for engaging against the side of said supporting bead opposite the side engaged by the end of 35 the neck of said shell.

2. A shade holder comprising a shell provided with shade or globe engaging means and having a threaded neck with an inturned edge, the upper end of said neck being adapted 40 to engage against the lower side of a shade holder supporting bead integral with the lower end of a socket shell, and a retaining ring having a threaded portion at one end capable of engaging said threaded neck 45 and provided with an inturned edge at the other end thereof capable of engaging the upper side of said supporting bead to clamp said shell against the lower side of said supporting bead.

50 3. The combination of a socket shell having a supporting bead near the lower end thereof, said bead providing a shoulder having an outer diameter greater than every part of the shell above it, a shade holder 55 having means near its lower edge for engaging a shade and provided with a threaded neck, the upper end of said neck engaging against the lower side of said bead, and a retaining ring having an integral inwardly

extending part of less inner diameter than 60 the bead resting on said shoulder and a threaded portion capable of engaging said threaded neck to clamp the upper end of the neck against the lower side of said bead.

4. A shade holder comprising a shell provided with a depressed portion having a hole therein, an interiorly threaded bushing secured in said hole and having a part disposed in the depressed portion of the shell, said depressed portion and the part of the 70 bushing fitting therein being other than circular in shape, whereby the bushing is locked against turning in said hole, and a shade retaining screw fitting said bushing.

5. A shade holder comprising a shell provided with rectangular outwardly pressed parts near the lower edge thereof, said parts having holes therein, interiorly threaded bushings secured in said holes and having rectangular flanges on the inner ends thereof 80 locked against turning by the rectangular outwardly pressed parts in the wall of said shell, and shade retaining thumb screws fitting said bushings.

6. A shade holder comprising a shell provided with shade or globe engaging means and having a threaded neck with a thickened edge, said thickened edge being adapted to engage against the lower side of a shade holder supporting bead integral with the 90 lower end of a socket shell, so as to bring the exterior of the threaded portion of the neck substantially even with the outer edge of the supporting bead, and a one-piece retaining device having a threaded portion at one end 95 capable of engaging said threaded neck and provided with an inturned edge at the other end thereof capable of engaging the upper side of said supporting bead to clamp said shell against the lower side of said supporting bead.

7. A shade holder comprising a shell provided with shade or globe engaging means and having a threaded neck, the upper edge of said neck being adapted to engage against 105 the lower side of a shade holder supporting bead integral with a socket shell, and a one-piece continuous retaining ring having a threaded portion at one end capable of engaging said threaded neck and also provided 110 with inwardly extending means at the other end thereof of less inner diameter than the bead for engagement against the upper side of said supporting bead to clamp said shell against the lower side of the bead.

In testimony whereof I affix my signature.

JAMES S. CROSSLEY.
